(57) **CLAIM**

The ornamental design for a grate for a refrigeration appliance as shown and described.

DESCRIPTION

FIG. 1 is a perspective view of a grate for a refrigeration appliance;

FIG. 2 is a front view thereof;

FIG. 3 is a perspective view of the grate on a refrigeration appliance;

FIG. 4 is a perspective view of the grate on a further refrigeration appliance; and,

FIG. 5 is a perspective view of the grate for a refrigeration appliance.

The evenly broken lines depict unclaimed subject matter only; the dash-dot broken lines disclose unclaimed boundaries of the claim; the broken lines form no part of the claimed design.

1 Claim, 5 Drawing Sheets---
